UNITED STATES PATENT OFFICE

146,171

DESIGN FOR A MOTION-PICTURE PROJECTOR

Ernest S. Carpenter, Shaker Heights, Ohio, assignor to The Augustus Carpenter Company, Cleveland, Ohio, a corporation of Ohio

Application August 8, 1946, Serial No. 132,354

Term of patent 14 years

(Cl. D61—1)

To all whom it may concern:

Be it known that I, Ernest S. Carpenter, a citizen of the United States of America, residing at Shaker Heights, county of Cuyahoga, State of Ohio, have invented a new, original, and ornamental Design for a Motion Picture Projector, of which the following is a specification, reference being had to the accompanying drawings, forming a part thereof.

In the drawings, Fig. 1 is a side elevation of a motion picture projector embodying my new design; Fig. 2 is a front elevation thereof; Fig. 3 is a rear elevation thereof; and Fig. 4 is a side elevation looking at the opposite side from Fig. 1.

I claim:

The ornamental design for a motion picture projector, as shown.

ERNEST S. CARPENTER.
